Louis M. Sanders ATTORNEYS.

UNITED STATES PATENT OFFICE.

WILLIAM B. MARQUARD, OF EASTON, PENNSYLVANIA.

COKING PROCESS.

1,323,711.

Specification of Letters Patent.

Patented Dec. 2, 1919.

Application filed January 2, 1919. Serial No. 269,324.

To all whom it may concern:

Be it known that I, WILLIAM B. MARQUARD, a citizen of the United States, residing in the city of Easton, county of Northampton, and State of Pennsylvania, have invented certain new and useful Improvements in Coking Processes, of which the following is a specification.

The retort by-product oven used most extensively in this country is a long narrow chamber, from 20 to 40 feet in length, about 7 feet high, and from 15 to 20 inches wide. The ovens are built in blocks or batteries, having from 20 to 90 ovens in each battery; adjoining ovens are separated by a flue in which the heating gas is burned to coke the coal with which the ovens are charged. The charge of coal is introduced into the ovens through openings in the top, after which the openings are sealed and the gas and other distillation products are led away through an opening to the collecting main. When the charge of coal is coked, which occurs in from 16 to 24 hours, the doors at the ends of the oven are removed and the coke is pushed out by means of rams or "pushers"; the oven doors are then immediately closed and sealed, and the oven is then ready for a fresh charge of coal. The liberated gases and distillation products pass from the collecting main and are exhausted into the condensing house where the gases are cooled and the by-products are removed. About one half of the gas is returned to the ovens to be burned in the flues, and the remainder is otherwise utilized as an additional by-product. My improvements are specifically applicable to the coking process as thus generally described.

The successful operation of a by-product coking plant depends mainly upon the uniformity of the heating of the ovens. Endless trouble results from irregular or non-uniform heating. One of the main considerations in securing uniform heating is the proper order of rotation in discharging the ovens. If there is a predetermined order of discharging the ovens, such order is called the "pushing series". My improvements relate to the selection of the best order of discharging the ovens, or in other words, the selection of the best pushing series to secure the greatest economy and efficiency in a coking plant.

Pushing series may be generally classified as "uniform" and "non-uniform" or "irregular". If there is a constant difference in the ages of every two adjacent ovens, the pushing series is called uniform; and if that difference is not constant, then the pushing series is called non-uniform or irregular. A uniform pushing series may also be defined as one in which the first oven at the right of any oven at the time of its discharge is always of the same age; likewise the age of the first oven on the left is always the same.

When a uniform pushing series is used, if the heating gas is burned uniformly in all of the flues, all of the ovens will receive identically the same heat treatment. With a non-uniform or irregular pushing series, the heating conditions may differ widely and some ovens may receive much more heat than others, notwithstanding the burners in the various flues are regulated to liberate a uniform amount of heat and the coking time is the same for all of the ovens. It must not be inferred that all uniform series are more efficient than some of the non-uniform series; the exact reverse is true in many cases. The ovens may be uniformly poorly heated.

The ideal condition for the greatest efficiency is such that the pushing series should be uniform, and such as to maintain a more clearly constant flue temperature. The temperature of the flue is dependent upon the difference in the ages of the adjoining charges of coal, provided the amount of heat liberated in the flues is constant. If the difference in the ages of the charges of two adjacent ovens is small, the flue between them is cooled down in the early part of the coking time, and consequently a lesser amount of heat can pass through the flue walls than could pass if the flue temperature remained constant or nearly so; while in the latter part of the coking time, when both ovens have a high temperature, the rate of flow of heat from the flue to the ovens is much reduced and consequently the heat in the flues must either be carried out with the products of combustion or the temperatures of the flues becomes very high. Practically, the flue temperature increases and as a result more heat is carried out of the flues by the products of combustion. Bear-

ing in mind that the rate of flow of heat varies directly as the difference in the temperatures of the flue and the oven walls, it will be seen that the ideal difference in the ages of adjacent ovens is exactly one half the coking time, because when the difference in ages is one half the coking time there is a more constant total flow of heat from the flue to the two adjacent ovens. Thus, if the oven to the left of a flue is newly charged and receives much heat, the oven to the right is half coked and receives considerably less heat; and hence, when the oven to the right is recharged and receives much heat, the oven to the left is half coked and receives a smaller amount of heat. Therefore, the flue temperature will be more uniform when the difference in the ages of adjacent ovens is one half of the coking time than it is when the difference in the ages of adjacent ovens is greater or less than one half the coking time.

My improvements, therefore, aim to meet the ideal conditions as nearly as practicable, by having:

- 1st. Uniform heat treatment of all ovens by establishing a uniform pushing series.
- 2nd. The difference in the ages of adjacent ovens as nearly as practicable one half of the coking time in order to maintain more uniform temperature of the flues.

A uniform and ideal pushing series can also be expressed in another way, namely: if, at the time any oven is discharged, the age of the first oven to the right is always the same and, likewise, if the age of the first oven to the left is always the same, the pushing series is uniform; and the ideal uniform series is one in which the age of the first right and the first left oven to any given oven is exactly the same. Since it is impracticable to have the ages of the first right and first left ovens exactly the same, the uniform series should be so selected that the first right and left ovens should be as nearly as possible of equal age; that is, as nearly as the best practice will permit.

In the accompanying drawings, I have illustrated by means of charts a uniform pushing series and several of the pushing series used in this country in such manner that the advantages or disadvantages flowing from their use may be readily ascertained, and the general laws relating to uniform series may be more easily deduced.

Figure 1 illustrating the 5-11 uniform pushing series, shows also by comparison, the relative ages of all of the ovens in the series, as well as the ages of the first adjacent ovens to any one being pushed, and also the difference in the ages of any two adjoining ovens.

Fig. 2 illustrates the 6-11 uniform push-

ing series, which, as hereafter described, is 65 the complement of the 5-11 series, and in all respects its full equivalent.

Figs. 3, 4, 5 and 6 illustrate respectively several of the irregular or non-uniform pushing series, and are given for the purpose of showing at a glance the extreme irregularity of such series as compared with a regular uniform series such as shown in Figs. 1 and 2, and also to enable us to analyze and make correct deductions of the effect of the uniform heating of the ovens. 75

In the following description, I shall first set forth the method of developing the various uniform pushing series, and then ascertain the results and advantages to be derived from the use of several of the best of these pushing series, and finally compare those results and advantages with the results and disadvantages flowing from the use of irregular or non-uniform series. 80

In order that a full understanding of the process may readily follow, I shall define some of the terms used.

The common practice at coke plants is to discharge every 10th oven in succession, and so the battery of ovens may be considered as containing a number of "cycles" of ovens, each cycle having 10 ovens. Thus, a battery of 50 ovens should contain five of such cycles, the ovens in the respective cycles being numbered from 1 to 10, 11 to 20, 21 to 30, etc. Ovens No. 1, 21, 31 and 41 are called "No. 1 ovens" of their respective cycles; likewise, ovens No. 4, 14, 24, etc., are the No. 4 ovens, etc. The pushing series is 95 then stated as the order or sequence of discharging the ovens of any cycle. The cycle may have any number of ovens, and although in general use, it will be shown that the 10-cycle pushing series are economically 100 poor and inefficient as compared with certain other pushing series where the cycle is other than 10.

In order to greatly simplify the determination of the ages of adjacent ovens in 110 a battery, and to develop uniform pushing series, I have coined the term "unit age", which may be defined as the coking time divided by the number of ovens in the cycle. Thus, when the coking time is 20 hours, the 115 unit age in a 10-cycle series is 2 hours; likewise, the unit age in a 15-cycle series becomes 20/15, or 1 hour and 20 minutes. The coking time is, therefore, equal to the number of ovens in the cycle in unit ages; thus, 120 in the 10-cycle, the coking time is 10 unit ages or 10 units; in the 15-cycle, the coking time is 13 units, etc.

In the development of the uniform pushing series, I have used two methods, both 125 of which reach the same results. I have called them respectively the "interval method" and the "phase method",

The "interval" may be defined as the difference in the ages (in units) of adjacent ovens. Thus, in the 3-interval 10-cycle series, (called the 3-10 series) each oven is 5 units older than the next oven to its right, and hence the relative ages of the ovens when oven No. 1 is pushed are shown by the following table:

Oven number	1	2	3	4	5	6	7	8	9	10
Relative age	10	7	4	1	8	5	2	9	6	3
Pushing order	1	4	7	10	3	6	9	2	5	8

It will be observed that, although each oven is 3 units older than the one to its right, yet the coking time 10 must be added to ovens No. 4, 7, and 10, for these ovens have ages 1, 2 and 3 respectively of the succeeding charge of coal.

Since the coking time is 10 units, oven No. 1 is pushed first; after one unit of time has elapsed, oven No. 8, which was 9 units old when oven No. 1 was pushed, has arrived at the coking time, and is pushed second; two units after No. 1, oven No. 5 is pushed; and so on, in the sequence given in the pushing order numbers. Thus, the pushing order or order in which all of the ovens of the cycle are pushed is determined.

From an examination of the table it will be observed that the sum of the pushing order and the relative age in units for any oven is always 11 in the 10-cycle pushing series. Upon the production of other series, it can be readily shown in general that the sum of the relative unit age and the number of the pushing order is always one greater than the number of ovens in the cycle. It may also be noted in any uniform pushing series, that the sum of the ages of the first ovens to the right and left of any oven at the time such oven is pushed, is equal to the coking time in units. Thus, in the 3-10 series, when any oven is pushed according to regular schedule, the age of the first oven to the right is 7 units, and the age of the first oven to the left is 3 units. It may also be noted that the pushing order can be determined directly when the interval is known, by merely adding the interval to the order number of the previous oven, thus, in the 3-10 series:

Oven number	1	2	3	4	5	6	7	8	9	10	1	2	3	etc.
Pushing order	1	4	7	10	3	6	9	2	5	8	1	4	7	etc.

Hence, if the interval is known, the pushing order in any series may be readily determined. For example, in the 5-11 series, the interval is 5 and the number of ovens in the cycle is 11, and there are 11 units in the coking time. Starting with oven No. 1, its age when pushed is 11 units; No. 2 oven is 5 units younger or its age is 6 units, and No. 3 oven is 1 unit old. The series fully developed is:

Oven No	A-cycle.					B-cycle.							
Rel. age	1	2	3	4	5	6	7	8	9	10	11	12	13
Push. order	1	6	11	5	10	4	9	3	8	2	7	1	6

The above table is shown fully developed in Fig. 1 of the drawings, with the ages of all of the ovens graphically illustrated. From a study of the figure or chart, it will be noted that when oven No. 1 is 11 units old 70 and ready to be pushed, oven No. 2, or the first oven to the right is 6 units old, and oven No. 11 or the first oven to the left is 5 units old. It will likewise be found that when each oven has matured to the coking 75 age the first oven to the right will be 6 units old and the first oven to the left will be 5 units old. It will also be observed that the sum of the first left and first right ovens equals 11 units, or the coking time. 80

The other method of developing the pushing order I have called the phase method. In this method the pushing order in the various series is first determined, and the relative ages of the ovens are then found from 85 the pushing order. If, commencing with oven No. 1, every n th oven of any cycle is pushed in rotation, n is called the phase. (Oven No. 1 follows the last oven of any cycle, and hence in using the phase method, we should 90 consider the oven numbers in a cycle as lying on the circumference of a circle). Thus, if every 3rd oven is pushed, 3 is the phase; likewise, in the 11-cycle series, if every 9th oven is pushed, 9 is the phase. In 95 any given cycle, there is a fixed number of possible uniform pushing series, and all of them may be found by using either the phase or the interval method. The interval method has an advantage over the phase 100 method, to be alluded to in the determination of the best uniform series.

Since the interval method and the phase method of formulating pushing series each give all the uniform series in any cycle, 105 there is obviously some relation existing between the interval and the phase, or some way of reducing the one to the other. This relation is given by the following formula:

$$P = \frac{aN+1}{I}, \text{ and } I = \frac{aN+1}{P}. \quad 110$$

In the foregoing formulae,
P is the phase number,
I is the interval number,
N is the number of ovens in the cycle, and
a is the smallest possible positive number
that will make the value of the fraction an
integer. 115

The following example will illustrate the 120 relations on a 13-cycle series:

Oven No.	1	2	3	4	5	6	7	8	9	10	11	12	13
A. push. Or	1	3	5	7	9	11	13	2	4	6	8	10	12
B. push. Or	1	6	11	3	8	13	5	10	2	7	12	4	9

In A. interval is 2, and phase is 7, since 125 every 7th oven is pushed.

In B. interval is 5, and phase is 8, since every 8th oven is pushed.

In C. interval is 6, and phase is 11, since 130 every 11th oven is pushed.

In order to determine the phases by the use of the formula:

5 In A. $P = \frac{aN+1}{I} = 7$. In this case, a is 1,
N is 13 and I is 2.

In B. $P = \frac{aN+1}{I} = 8$. In this case, a is 3,
N is 13 and I is 5.

10 In C. $P = \frac{aN+1}{I} = 11$. In this case, a is 5,
N is 13 and I is 6.

(In each case, a is given the smallest value that will make the fraction an integer.)

15 In any given cycle, the interval number and also the phase number must be prime to the number of the cycle, that is, it cannot be a factor of, nor contain a factor that is common to, the cycle number. Thus, in 20 the 10-cycle series, the only possible interval or phase to give a uniform series is 3 and 7, both of which are prime to 10. The other numbers not being prime, any attempt 25 to formulate a uniform series with them as intervals or phases would be futile. Complementary series are found by merely reversing the direction in both the interval and phase method, and hence are fully 30 equivalent in efficiency. In the 10-cycle series, the 3-interval is complementary to the 7-interval; also the 3-phase is complementary to the 7-phase. Likewise in the 35 11-cycle series, the 4 interval or phase is complementary to the 7 interval or phase; the 5 and 6 intervals are also complementary, as is graphically illustrated in Figs. 1 and 2, and as previously stated, the 5-11 and the 6-11 series are identical in 40 form with the order of pushing reversed. Every uniform series, therefore, has its complementary series; in other words, uniform series occur in pairs, the interval or phase of any series being equal to the cycle number 45 minus the interval or phase of the complementary series. The 11-cycle series may have the following intervals: 2, 3, 4, 5, 6, 7, 8 and 9, since all of these numbers are prime to 11; yet there are four distinct series only, 50 since 2 and 9, 3 and 8, 4 and 7, 5 and 6 are respectively complementary intervals or phases.

We are now able to develop all the regular pushing series, no matter what the cycle 55 may be; as above indicated, this may be done either by the interval or by the phase method. In order, however, that the relative merits of the various pushing series should be made apparent, the following 60 comparisons should be made:

1st. Whether or not the pushing series is uniform.

2nd. The difference in the ages of any two adjoining ovens.

65 3rd. The sum and the difference of the

ages of the first adjacent ovens on either side of any oven when such oven is pushed.

1st. If the pushing series is uniform, all ovens should receive the same heat treatment, and conversely if all the ovens receive the same heat treatment, the pushing series must be uniform. It is perfectly obvious that the pushing series should be uniform if a good uniform series could be selected and were practicable.

2nd. The difference of the ages of any two adjoining ovens should be as nearly as practicable equal to one half the coking time, in order, as already stated, that the flue temperatures may be maintained more nearly constant. Therefore, a good uniform series is one in which the interval is as nearly as possible one half of the coking time. It will therefore be noted that an even number of ovens in a cycle is not as good or as efficient as an odd number, because in an even numbered cycle, the number nearest to one half the cycle number is exactly one half that number, and therefore not prime to it. This leads to the conclusion that the best 90 and most efficient cycle numbers must be odd. Furthermore, the best interval is de-

termined by the formula $\frac{n \pm 1}{2}$, where n is the number of ovens in the cycle and odd. Thus, in the 9 cycle, the best interval is 4 or 5, and as above set forth, these are complementary. Likewise, in the 11-cycle, the best interval is 5 or 6, etc. In case the cycle has an even number of ovens, the interval 100 nearest to one half the coking time is determined by the formula $\frac{n \pm 2}{2}$, where n is

the number of ovens and $\frac{n}{2}$ is even; or by 105 the formula $\frac{n \pm 4}{2}$, when $\frac{n}{2}$ is an odd number. It is thus apparent that the best number of ovens in the cycle is an odd number; 110 the second best is an even number where $\frac{n}{2}$ is even, and the poorest when $\frac{n}{2}$ is an odd number. Hence, a uniform series on the 10-cycle which is the one in common use is a 115 very poor uniform series.

When the best interval in any odd numbered series is selected, the difference in the ages of any two adjoining ovens is $\frac{1}{2}$ unit more or less than $\frac{1}{2}$ the coking time, and consequently, since it is desired that this difference be as near as practicable to $\frac{1}{2}$ of the coking time, the unit of time should be as small as we can make it; this is done 120 by increasing the number of ovens in the cycle. There is, however, a practical limit to the number of ovens in the cycle, for the reason that congestion of working about the oven being charged and the oven being dis-

charged is not desirable or economical; furthermore, a long travel of the pushing and leveling machines, door extractor and clay carriers is not economical.

- 5 3rd. It was observed that in all uniform series, the sum of the ages of the first adjacent ovens to the right and left of any given oven when said oven is pushed, is equal to the coking time, and hence since the 10 ages of such right and left ovens should be as nearly equal as possible, they should each have an age as near to $\frac{1}{2}$ the coking time as possible, or what amounts to the same thing, the difference in their ages 15 should be as small as possible. This method of consideration leads to exactly the same results obtained in the next preceding paragraph.

In order that the advantages of my improved coking process may be made more apparent, I have shown graphically in Figs. 3, 4, 5 and 6 several of the pushing series now in use. Take for example the series shown in Fig. 3, which is as follows:

25	Oven number.....	1 2 3 4 5 6 7 8 9 10
	Pushing order.....	1 5 9 7 2 4 10 6 8 3
	Relative age.....	10 6 2 4 9 7 1 5 3 8

Referring to the above table or to Fig. 3, it will be noted that this is an irregular or non-uniform pushing series, and that the difference in the ages of adjoining ovens beginning with Nos. 1 and 2 are 4, 4, 2, 5, 2, 4, 2, 5, 2 units respectively. Two of the flues only are well heated, while in four of the flues the difference in the ages of adjoining ovens is only 2 units or $3\frac{1}{2}$ hours on $17\frac{1}{2}$ hour coke. The flue temperatures are, therefore, necessarily far from constant. Hence, the various ovens do not receive similar heat treatment. A similar examination of the pushing series illustrated in Figs. 4, 5 and 6 would show similar results as to heat treatment.

The unequal heating of the oven walls that results from the use of an irregular or non-uniform pushing, or the poor heating conditions resulting from a poor uniform series, gives rise to many of the difficulties in the operation of by-product coking plants. 50 Some of these may be enumerated as follows: In irregular pushing series, more heat will enter through one of the oven walls than through the other, and the central parting of the coke will not come in the center of the charge, consequently resulting in a non-uniform coke. Again, in an irregular pushing series, the coking time is necessarily limited to that of the most slowly heated oven, and thus certain other ovens 55 that are more favored by the pushing series will suffer by being overheated, while there will be a probable discharge at high temperature of the volatile hydrocarbons which are cracked by these high temperatures, with

a resulting decrease in the yield of the by-products. The sticking of the coke charges in the ovens is traceable directly to unequal and irregular heating. Since the determination of the coking time, as above stated, is greatly controlled by the ovens found to 70 be the most difficult to heat, it follows that by the use of a good uniform pushing series a reduction of the coking time must result, and the efficiency and capacity of the plant correspondingly increased. 75

These and other advantages flowing from the use of a good uniform pushing series as distinguished from an irregular or from a poor uniform series may be thus summarized:—

80 A good uniform series will—

1st. Reduce the amount of gas burned in the oven flues, and consequently increase the amount of surplus gas.

2nd. Reduce the coking period or time to 85 a minimum, because of less danger of irregular heating, and consequently increase the capacity of the plant.

3rd. Improve the quality of the coke.

4th. Increase the yield of the by-products. 90

5th. Diminish the number of stickers, and consequently the number of ovens that are temporarily out of commission.

6th. Increase the life of the plant.

7th. Diminish the operating expenses of 95 the plant.

The prevailing practice at the by-product coking plants where a pushing series is used is to use some series on the 10-cycle. It has therefore not been necessary to differentiate 100 the various cycles in any way other than the direct method of consecutive numbers. However, when any cycle other than 10 is used, it becomes advisable if not absolutely necessary to distinguish the cycles and the 105 various ovens in the several cycles. This can be done in several ways. If there are 9 ovens in the cycle, the numbers 10, 20, 30, etc., may be omitted. If there are 11 ovens in the cycle, an extra number of a different 110 notation may be inserted in each 10, thus:— 1, 2, 3, —8, 9, 10, X, 11, 12, —19, 20, 2X, 21, 22, etc. Where there are more than 10 ovens in a cycle, I prefer to give each cycle a designating letter, as A, B, C, D, etc., and then 115 number the ovens of each cycle consecutively. Thus, 4A is the 4th oven of the first cycle; 7B is the 7th oven of the 2nd cycle, etc. By thus distinguishing the ovens in this or any similar way, there is far less 120 confusion with regard to pushing the proper ovens; for example: all of the 1's are pushed in all of the cycles, and then, say, all of the 3's, etc. When it is considered that the workmen who are actually 125 engaged in operating the plant are not usually of a high order of mentality, the importance of a simple method of designating

the ovens and cycles cannot be overestimated, particularly where there is a change from existing conditions.

From the foregoing, it will be seen that I have added an important improvement to existing coking processes, and I therefore desire to claim the same broadly.

I claim:—

1. A coking process consisting of arranging a battery of coking ovens in a series of cycles, each cycle containing a number of ovens, and thereafter charging and discharging said ovens in such regular order that the difference in the ages of every two adjoining ovens shall be constant.

2. A coking process consisting of arranging a battery of coking ovens in a series of cycles, each cycle containing N ovens, and thereafter charging and discharging said ovens in such order that the difference in the ages of every two adjoining ovens shall be $\frac{N \pm 1}{2}$ units of time when N is an odd number;

3. A coking process consisting of arranging a battery of coking ovens in a series of cycles, each cycle containing $N/2$ ovens, and thereafter charging and discharging said ovens in such order that the difference in the ages of every two adjoining ovens shall be $\frac{N \pm 4}{2}$ units of time when $N/2$ is an odd number.

4. A coking process consisting of arranging a battery of coking ovens in a series of cycles, each cycle containing the same number of ovens, and thereafter charging and discharging said ovens in such order that the difference in the ages of every two adjoining ovens shall be constant.

5. A coking process consisting of arranging a battery of coking ovens in a series of cycles, each containing an odd number of ovens, and thereafter charging and discharging the ovens in any cycle in a regular order such that every n th oven of each cycle shall be discharged in turn, where n is a number prime to the number of ovens in each cycle.

6. A coking process consisting of arranging a battery of coking ovens in a series of cycles, each cycle containing a number of ovens, and thereafter charging and discharging said ovens in a regular order such that every n th oven of each cycle shall be discharged in turn, where n is a number prime to the number of ovens in each cycle.

7. A coking process consisting of arranging a battery of coking ovens in a series of cycles, each containing an odd number of ovens, and thereafter charging and discharging said ovens in such order that the difference in the ages of the ovens immediately adjacent to the right and left of any given oven shall be constant in the several cycles.

7. A coking process consisting of arranging a battery of coking ovens in a series of cycles, each containing an odd number of ovens, and thereafter charging and discharging said ovens in such order that the difference in the ages of the ovens immediately adjacent to the right and left of any given oven being discharged shall be the coking time divided by the number of ovens in the cycle.

8. A coking process consisting of arranging a battery of coking ovens in a series of cycles, each cycle containing an odd number of ovens, and thereafter charging and discharging said ovens in such regular order that the sum of the ages of the ovens immediately adjacent to the right and left of the oven being discharged shall be equal to the coking time.

9. A coking process consisting of arranging a battery of coking ovens in a series of cycles, each cycle containing an odd number of ovens, and thereafter charging and discharging said ovens in such regular order that the age of every oven shall be less than the age of the oven next adjacent thereto by a number of unit ages that is prime to the number of ovens in the cycle.

10. A coking process consisting of arranging a battery of coking ovens in a series of cycles with the same number of ovens in each cycle, and thereafter charging and discharging said ovens in such regular order that the difference in the ages of the ovens immediately adjacent to the oven being discharged shall be uniform.

11. A coking process consisting of arranging a battery of coking ovens in a series of cycles, each containing the same odd number of ovens, and thereafter charging and discharging said ovens in such regular order that the respective ovens as they are discharged shall have attained the coking time, and the two ovens immediately adjoining the one being discharged shall have attained ages whose sum shall equal the coking time.

12. A coking process substantially as set forth in claim 1, in which the ovens of each cycle are consecutively numbered, and the several cycles are designated by a distinctive symbol.

13. A coking process substantially as set forth in claim 2, in which each cycle is designated by a distinctive letter as A, B, C, etc., and the ovens of each cycle are consecutively numbered.

14. A coking process substantially as set forth in claim 4, in which each cycle is designated by a distinctive symbol, and the ovens of each cycle are consecutively numbered, whereby to facilitate their regular and uniform operation.

W. B. MARQUARD.
